UNITED STATES PATENT OFFICE.

FRANCIS RITCHIE, OF TROY, NEW YORK, ASSIGNOR TO ISAAC A. SHEPPARD, FRANKLIN L. SHEPPARD, AND HOWARD R. SHEPPARD, OF PHILADELPHIA, PENNSYLVANIA.

DESIGN FOR A COOKING-STOVE.

SPECIFICATION forming part of Design No. 21,615, dated June 7, 1892.

Application filed May 12, 1892. Serial No. 432,790. Term of patent 14 years.

To all whom it may concern:

Be it known that I, FRANCIS RITCHIE, a citizen of the United States, and a resident of Troy, Rensselaer county, New York, have invented a new and original Design for a Cooking-Stove, of which the following is specification.

My design for a cooking-stove is fully illustrated in the accompanying drawing, the figure of which represents the stove in perspective.

The stove is of the class having a base, a body portion, a projecting ash-pit, and an overhanging oven-section. On the oven-door are three sets of scrolls, one set having its base at the upper hinge and curving over the central name-plate and another set having its base at the lower hinge and extending under the name-plate, which in the present instance is oval and has a diagonal band across its field. The third scroll on the door is centered at the knob and extends toward the name-plate. The side fire-door has a single scroll having its base at the hinge. This scroll is in keeping with the scrolls on the oven-door. On the face of the hot-water compartment is a double scroll having its base at

the spigot and extending upward at each side. A cross-scroll extends above the spigot, overlapping the double scroll. The warming-oven door has two sets of scrolls, one set extending from the upper hinge and the other set extending from the lower hinge, the scrolls incasing a central rosette on the door. On the base are scrolls extending from the center of each side panel toward the corners. These scrolls are in keeping with the scrolls on the doors, and the other ornamentation of the stove is also in keeping with the general design.

The main features of the design are the scrolls having their bases at the hinges or at some projecting point on the stove.

I claim—

The design for the ornamentation of a cooking-stove, as herein described, and shown in the accompanying drawing.

In testimony whereof I have signed my name to this specification in the presence of two subscribing witnesses.

FRANCIS RITCHIE.
